UNITED STATES PATENT OFFICE.

CHARLES F. MASSEY, OF CHICAGO, ILLINOIS.

RAILWAY-SIGNAL POST.

1,070,504.

Specification of Letters Patent. Patented Aug. 19, 1913.

Application filed November 23, 1910. Serial No. 593,803.

To all whom it may concern:

Be it known that I, CHARLES F. MASSEY, a citizen of the United States, residing at Chicago, in the county of Cook and State 5 of Illinois, have invented certain new and useful Improvements in Railway-Signal Posts, of which the following is a specification.

My invention relates to railway signal 10 posts and contemplates improved construction and arrangement.

Among the important objects of my invention are to provide a post which is entirely constructed of cementitious material 15 such as concrete through which extends longitudinally a metallic pipe which serves both as an electrical conductor for wires and also as a reinforce for the concrete; to provide a head frame for the post formed integral therewith of concrete and providing a compartment for receiving signal lamps or other apparatus or for accommodating semaphore apparatus; to provide a dust and weather-proof compartment at an intermediate 20 part of the post for receiving relays or other electrical apparatus, the walls of which compartment are formed integrally of concrete with the post; to provide an improved bed structure for the post, which 25 structure is built up integrally of concrete and which, besides affording a seat or anchorage bed for the post, is arranged to provide a well or housing for batteries; and 30 in general to provide a construction and arrangement 35 which will better adapt signal posts for usage in up-to-date railway signaling systems.

In the drawing which accompanies this specification Figure 1 is a front elevational view of the post, Fig. 2 is a sectional view 40 taken on plane 2—2, Fig. 1, Fig. 3 is an enlarged sectional view taken on plane 3—3, Fig. 1, and Fig. 4 is a cross sectional view 45 of the post taken on plane 4—4, Fig. 1 to illustrate more clearly the concrete reinforcing arrangement.

The post 5 may be of rectangular cross section, as indicated in Fig. 4, and has the widened or enlarged base 6 and at its top 50 is expanded to form the annular top frame 7 of substantially rectangular cross-section, as indicated in Fig. 2. At an intermediate part the post is hollowed and expanded laterally and forwardly to provide top and 55 bottom walls 8 and 9 and side walls for a compartment 12. The post proper, the top

frame 7, and the walls 8, 9, 10 and 11 form an integral structure preferably built up of concrete C. Extending centrally and longitudinally through the post is a metallic pipe 60 13, this pipe serving as a conduit for electric circuit wires. The post may be reinforced by longitudinal metallic bars 14, suitably cross connected at intervals by wires 15, as indicated in Fig. 4, these bars preferably being 65 extended through the body of the annular top frame 7, as indicated in Fig. 2, in order to strengthen this top frame. The pipe 13 is interrupted to connect with the upper and lower ends of compartment 12. The 70 pipe may also have the sleeve 16 interposed, from which an outlet pipe 17 leads to a frame 18 suitably secured to a face of the post and accommodating electric bell mechanism 19. As best shown in Fig. 1, the pipe 75 13 terminates at its upper end in a four-way fitting 20 from whose side outlets extend semicircular pipe sections 21 and 21' through the respective halves of the concrete top frame 7, the upper ends of the 80 pipe sections connecting in the lateral outlets of the four-way fitting 22 at the top of frame 7. A stud plate 23 extends from the upper outlet of fitting 22 and through a boss or extension 24 at the top of frame 7, 85 this boss or extension serving to support an electrically controlled signal bell 25. The lower end of the pipe has the lateral outlet 26 through which the external circuits may enter.

The pipe 13 assists in reinforcing the concrete of which the post is constructed, and likewise the pipe sections 21 and 21' will assist in strengthening and reinforcing the top frame 7. The reinforcing of the 90 post may follow along the walls of compartment 12 to strengthen these walls. This compartment serves for the accommodation of any desired electrical apparatus A, such as relays and line protecting mechanism, 95 and in order to render this compartment more dust-proof and weather tight it is preferably lined with some suitable material 27 and provided with a main door 28 and an auxiliary door 29. The main door 100 is hinged at 30 to one side wall of the compartment, and may be locked by suitable lock mechanism 31. Interposed between the main door and the auxiliary door is a compression spring 32 which, when the main 105 door is closed, bears against the auxiliary door to securely hold the auxiliary door to

the lining 27, a gasket 33 of suitable material such as felt being preferably interposed between the auxiliary door and the front edges of the lining 27. Thus, when the doors are closed no dust, dirt or moisture can enter compartment 12, and the electrical apparatus in said compartment is therefore amply protected. The top wall 8 overhangs the main door, as indicated at 34, to form 10 an eave, and in the under side of this eave is provided a drip groove 35.

The frame 7 at its opposite inner edges has grooves 37 and 38 forming a seat for glass disks 39 and 40, these disks, together 15 with the frame 7, forming an inclosed compartment 41 in which, as shown, is accommodated an electric lamp 42, which, as shown, may be suspended by pipe 43 from the top fitting 24. The glass disk may have 20 painted thereon any suitable legends, such as indicated in Fig. 1, and the disks are held in place in their grooves by clips 44 extending from the frame 7.

As indicated in Fig. 2, the post is supported in upright position by an integral concrete structure S which provides a 25 pocket 45 for the base of the post and which also provides a compartment 46 in which batteries may be stored or in which electrical distributing apparatus may be installed, the compartment being accessible through an opening 47 having a cover 48. The extension 26 at the lower end of the pipe leads 30 into compartment 46. Where permissible 35 the integral foundation structure providing both a well and a support for the post will be installed. In other cases the post can be set in an ordinary foundation and a separate well installed at a suitable point and connected with the conduit pipe in the 40 signal post.

The post of my invention is of very rigid

and permanent construction which is not affected by the elements. The various relays and other controlling mechanism are securely housed directly on the post adjacent 45 the signaling apparatus which they control and are well protected against the weather and particularly dust, cinders, soot, smoke, etc. Where the post bed and the battery 50 well are part of an integral structure the well and post will serve mutually to support each other in proper position.

I do not desire to be limited to the precise construction and arrangement which I have 55 shown, as changes and modifications are of course possible which would still come within the scope of my invention, and I therefore claim the following:

A railway signaling post structure entirely of concrete and expanded at intermediate parts to form a compartment for accommodating signaling mechanism, the top of said concrete structure being expanded into the form of a circular head, transparent 60 sides applied to said circular head to form therewith a compartment for housing signaling mechanism, a pipe extending entirely around and within the material of the circular head to form a reinforce therefor, a 70 pipe extending longitudinally through said post and communicating at its upper end with the interior of the head piping, an outlet from said head piping to the head compartment, and a concrete supporting base having 75 a socket for receiving the lower end of said post.

In witness hereof, I hereunto subscribe my name this 21st day of November, A. D., 1910.

CHARLES F. MASSEY.
